(57) CLAIM

The ornamental design for a watch casing, as shown and described.

DESCRIPTION

FIG. 1 is a top plan view for a watch casing showing our new design;

FIG. 2 is a left side elevational view thereof;

FIG. 3 is a right side elevational view thereof;

FIG. 4 is a first end elevational view thereof;

FIG. 5 is a second end elevational view thereof; and,

FIG. 6 is a bottom plan view.

The broken-line showings are environmental only and form no part of the claimed design.
